UNITED STATES PATENT OFFICE

1,942,055

WELDING APPARATUS

Ralph A. Gilbert, Pittsfield, Mass., assignor to
General Electric Company, a corporation of
New York

Application June 21, 1932. Serial No. 618,445

6 Claims. (Cl. 219—8)

My invention relates to arc welding and more particularly to that form of arc welding in which the work is subjected to the action of an arc maintained between a plurality of electrodes. 5 When operating thus with the arc in contact with the work there is a voltage between each electrode and the work even though the work is not connected in the welding circuit. This voltage increases and decreases as the distance between 10 the arcing terminals of the electrodes and the work increases and decreases.

It is an object of my invention to provide means for automatically controlling the position of the arcing terminals of a plurality of electrodes relative to the work when said electrodes are connected in a welding circuit independently of the work for performing a welding operation in which the welding arc is maintained in contact with the work. 15

20 My invention will be better understood from the following description taken in connection with the accompanying drawing which diagrammatically illustrates one embodiment thereof.

In the particular arrangement illustrated a 25 plurality of electrodes 1 and 2 are connected by conductors 3 and 4 to a source of welding current, not shown. These electrodes are held by supports 5 and 6 with their arcing terminals within arcing distance of one another and the 30 work 7. In the particular arrangement illustrated, support 6 is fixed and support 5 is movable, being attached to one end of a bell crank lever 8, the other end of which is provided with a finger piece 9. This lever is pivoted at 10 and 35 normally biased into engagement with a stop 11 which determines the separation of the electrodes by positioning support 5 relative to support 6. The operator by depressing finger piece 9 can rotate lever 8 about pivot 10 and bring the electrodes into engagement with one another by displacing support 5 toward support 6. When the bell crank lever is then permitted to swing back to the position illustrated, the electrodes are separated and an arc is struck between them. 40

45 Electrodes 1 and 2 are fed toward and away from one another and the work by reversible feed motors 12 through the agency of speed reducing gears 13 and feed rolls 14. The feed motors may be connected to a source of supply 15 through 50 conductors 16, their fields 17, contacts 18 and 19 and conductors 20 for one direction of rotation or through conductors 16, their fields 21, contacts 19 and 22 and conductors 20 for the reverse direction of rotation. The connection of feed motors 12 to source of supply 15 is determined by the

movement of contacts 19 into and out of engagement with contacts 18 and 22. Contacts 19 are supported on armatures 23 of voltage relays 24 whose operating coils 25 are connected through conductors 26 and resistances 27 to the electrodes 60 and the work 7 so as to be responsive to the voltage between these electrodes and the work. Mov- 65 able contacts 19 are biased into engagement with fixed contacts 18 by springs 28 and are moved into engagement with fixed contacts 22 against the action of these springs by the energization of coils 25 when the voltage between the electrodes and the work 7 attains a predetermined value determined by the adjustment of resistances 27. The voltage difference between the electrodes 70 and the work 7 varies as the distance between their arcing terminals and the work and the ar- 75 rangement thus provided constitutes means for maintaining the arcing terminals of electrodes 1 and 2 at a predetermined distance from the work. 75

When the arcing terminal of either electrode is displaced from the work sufficiently to generate a voltage great enough to move contact 19 into engagement with contact 22 the feed motor 12 is energized by a circuit completed through field 80 21 and operates the feed rolls 14 in a direction to feed the electrode toward the work. This feed- 85 ing operation continues until a predetermined voltage and separation of the electrode from the work has been attained when the movable 85 contact 19 moves to the position illustrated in the drawing. If the arcing terminal of either electrode approaches too close to the work 7, the feed motor 12 is energized through contacts 18 and 19 of relay 24 to complete its circuit through field 90 17 and rotates in the opposite direction, withdraw- 95 ing the electrode from the work.

It is to be understood, however, that in ac- 95 cordance with my invention other feeding means responsive to the voltage between the electrodes and the work may be employed for positioning the arcing terminals of the electrodes a predetermined distance from the work when operating with the electrodes established between the electrodes in contact with the work. 100

Preferably the electrodes are inclined to one another, as illustrated in the drawing, to deflect the arc into engagement with the work by means of the magnetic field established between them. The electrodes may be arranged in other posi- 105 tions relative to one another and the arc be- 110 tween them deflected toward the work by elec- 115 tronmagnets or jets of gas. Various gases may be used, and my invention is particularly applica- 120 ble to apparatus designed for the utilization of 110

the heating effects of flames of atomic hydrogen. Hydrogen, for example, when directed across an electric arc is dissociated into its atomic state and when directed into engagement with the part to be welded recombines to its molecular state, liberating enormous amounts of heat. The utilization of atomic hydrogen flames is disclosed and claimed broadly in the copending application of Irving Langmuir, Serial No. 729,185, filed July 30, 1924, for Heating processes and apparatus, which application is assigned to the same assignee as the present application.

Referring to the drawing, the electric arc appears as there illustrated to have a core portion 29 which is surrounded by a flame 30 which is irregular in shape and in constant motion. When a combustible gas is supplied to the arc, such, for example, as hydrogen, the gas flame and the arc flame intermingle and are difficult to distinguish from one another. In order to attain the regulation above described it is not necessary that the arc core 29 come into direct engagement with the work since a voltage will appear between the electrodes and the work if the arc flame is in engagement with the work. The arc discharge may extend a short distance beyond the flame and consequently my apparatus may function with the visible part of the arc out of engagement with the work though as a matter of fact the arc is in engagement with the work.

My invention is applicable to direct current welding as well as to alternating current welding and single phase or polyphase alternating current may be employed. With polyphase alternating current each electrode is connected to one of the phase conductors and is controlled by a feed motor, as described above in connection with the arrangement illustrated, which is suitable for direct current welding or single phase alternating current welding.

Although I have described my invention in connection with arc welding apparatus, it is to be understood that it is applicable to other arrangements in which an article is heated by an arc established between a plurality of electrodes is directed onto the article in any suitable manner.

What I claim as new and desire to secure by Letters Patent of the United States is:

1. Apparatus comprising a plurality of electrodes, means for maintaining an arc between said electrodes, means for directing said arc onto

an article to be heated and means for independently feeding each electrode toward and away from said article in response to the voltage between said electrode and said article.

2. Apparatus comprising a plurality of electrodes, means for maintaining an arc between said electrodes, means for directing said arc onto an article to be heated, and means responsive to the voltage between said electrodes and said article for maintaining the arcing terminals of said electrode at a predetermined distance from said article.

3. Welding apparatus comprising a plurality of electrodes, means for maintaining an arc between said electrodes, means for feeding said electrodes toward and away from one another and the work, and means responsive to the voltage between said electrodes and the work when operating with the arc in contact with the work for positioning the arcing terminals of said electrodes a predetermined distance from the work.

4. Welding apparatus comprising a plurality of electrodes, means for supporting said electrodes with their arcing terminals within arcing distance of one another and the work, means for maintaining an arc between said electrodes and means for independently feeding each electrode toward and away from the work in response to the voltage between said electrode and the work.

5. Welding apparatus comprising a plurality of electrodes, means for supporting said electrodes in inclined positions relative to one another with their arcing terminals within arcing distance of one another and the work, means for maintaining an arc between said electrodes, and means responsive to the voltage between said electrodes and the work when operating with the arc in contact with the work for maintaining a predetermined arcing condition between said electrodes and the work.

6. Welding apparatus comprising a plurality of electrodes, means for supporting said electrodes with their arcing terminals within arcing distance of one another and the work, means for maintaining an arc between said electrodes and means responsive to the voltage between said electrodes and the work when operating with the arc in contact with the work for maintaining a predetermined arcing condition between said electrodes and the work.

RALPH A. GILBERT.
